UNITED STATES PATENT OFFICE

127,121

DESIGN FOR AN ELECTRIC GRILL

Dimitri George Andrews Zeppos, Detroit, Mich.

Application February 27, 1941, Serial No. 99,250

Term of patent 14 years

To all whom it may concern:

Be it known that I, Dimitri George Andrews Zeppos, a subject of the King of Greece, residing at Detroit, in the county of Wayne and State of Michigan, have invented a new, original, and ornamental Design for an Electric Grill, of which the following is a specification, reference being had therein to the accompanying drawings, forming part thereof.

Fig. 2 is a side elevational view of one side of the grill;

Fig. 3 is a side elevational view of the opposite side thereof:

Fig. 4 is a plan view of the grill, and

Fig. 5 is a horizontal section on line 5—5 in Fig. 1.

I claim:

The ornamental design for an electric grill, as shown.

DIMITRI GEORGE ANDREWS ZEPPOS.
